Patented Nov. 21, 1967

209,276

DOOR CLOSER

Sidney W. Mowrer, Jr., Ashland, Ohio, assignor to Shelby Corporation, Shelby, Ohio, a corporation of Ohio

Filed Feb. 3, 1966, Ser. No. 900

Term of patent 14 years

(Cl. D10—7)

FIG. 1 is a top plan view of the door closer of present invention;

FIG. 2 is a side elevational view of the door closer of my present invention;

FIG. 3 is a bottom plan view of the door closer of my present invention;

FIG. 4 is an end view of the door closer of my present invention being taken along the line 4—4 of FIG. 2; and

FIG. 5 is an end view of the door closer of my present invention being taken along the line 5—5 of FIG. 2.

I claim:

The ornamental design for a door closer, as shown.
